CLAIM

The ornamental design for a cybernetic computer enclosure, as shown.

DESCRIPTION

FIG. 1 is a frontal orthogonal view of the cybernetic computer enclosure showing my new design;

FIG. 2 is a supplemental frontal, orthogonal view thereof;

FIG. 3 is a supplemental frontal view thereof;

FIG. 4 is a supplemental rear, orthogonal view thereof;

FIG. 5 is a supplemental side view thereof;

FIG. 6 is a supplemental side view thereof; and,

FIG. 7 is a supplemental rear, orthogonal view thereof.
